CLAIM

The ornamental design for a printer, as shown and described.

DESCRIPTION

FIG. 1 is a top and left side perspective view of a printer showing our new design;

FIG. 2 is a top plan view thereof;

FIG. 3 is a front elevation thereof;

FIG. 4 is a rear elevation thereof; and,

FIG. 5 is a left side elevation thereof, the side opposite being a mirror image.

The broken lines showing of portions of the design are included for the purpose of illustrating environmental structures and form no part of the claimed design.
